(57) **CLAIM**

The ornamental design for a sternum suture wire, as shown and described.

DESCRIPTION

This is a wire to suture sternum during a cardiovascular surgery.

FIG. 1 is a front elevational view of a sternum suture wire, showing my new design;

FIG. 2 is a left side elevational view thereof;

FIG. 3 is a right side elevational view thereof;

FIG. 4 is a top plan view thereof; and,

FIG. 5 is a bottom plan view thereof.
